(57) **CLAIM**

The ornamental design for a hook-up station with insulating jacket for solar-power system, as shown.

DESCRIPTION

FIG. 1 is a perspective view of a hook-up station with insulating jacket for solar-power system showing my new design;

FIG. 2 is a perspective view thereof, in a separated condition with the hook-up station removed for ease of illustration;

FIG. 3 is a right side elevation view of FIG. 1; and,

FIG. 4 is a perspective view of the hook-up station of FIG. 1 separated from the insulating jacket for ease of illustration.

The broken lines shown represent unclaimed subject matter and form no part of the claimed design.
